UNITED STATES PATENT OFFICE.

HARRY J. MARKS, OF MAMARONECK, NEW YORK.

APPARATUS FOR CONTROLLING STEAM-SUPPLY TO HEATING SYSTEMS.

1,178,170.

Specification of Letters Patent. Patented Apr. 4, 1916.

Application filed August 20, 1915. Serial No. 46,517.

To all whom it may concern:

Be it known that I, HARRY J. MARKS, a citizen of the United States, and a resident of Mamaroneck, in the county of Westchester and State of New York, have invented certain new and useful Improvements in Apparatus for Controlling Steam-Supply to Heating Systems, of which the following is a specification.

10 My invention relates to heating systems in which steam is the fluid vehicle of transmission and distribution; and my object is to adequately control the initial steam supply and pressure in such manner as to prevent waste thereof and utilize fully the calorific value of the steam used, as herein-after more fully set forth, a distinctive feature of the invention consisting in the provision of means whereby the steam is abstracted intermittently from the source of supply for use in the system in such manner that its expansive properties are effectually conserved and utilized, in contra-distinction to the old method of supplying the steam 25 to the heating system at full pressure in a direct, uniform and continuous flow from the source of supply. In other words I interpose between the heating system and the initial steam supply and pressure intermittent means for controlling the admission of steam to the heating system whereby the pressure is forthwith reduced to the operative requirements of the system, the latent heat by co-efficient expansion is more effectually utilized, and the waste incident to a continuous rush of steam at initial pressure to and through the system is obviated.

In the accompanying drawings I illustrate diagrammatically and symbolically 40 means for effecting the practical application and operation of my invention; Figure 1, being a sectional elevation showing the relation of essential elements; and Fig. 2, being an elevation of thrust and speed 45 mechanism adapted to effect the adjustment of stroke and speed of the controlling valve.

In the aforesaid drawing B, represents a boiler or other source of steam supply at initial pressure, and H, a steam conduit 50 communicating with the heating system to

be furnished with steam as a fluid vehicle for the transmission of the heat required. Interposed in the steam conduit b, b', between the steam source B, and the conduit H, to the heating system, is a controlling 55 valve which may be of any desired or well known construction, as may be found most expedient in adapting the invention and apparatus to the various requirements of use,—the essential feature in this respect 60 being a valve C, controlling a port c, in the steam conduit b, b',—the latter, b', being the portion of the steam conduit beyond the port c; and said port c, in this representation of parts, being constituted by the seat 65 for the valve C.

Any means desired may be employed to operate the valve C, intermittently, there being various well known mechanical expedients that may obviously be substituted 70 with like effect for this purpose in lieu of the particular device shown in the drawings,—in which a spring s, interposed between the valve casing and a shoulder c² on the valve stem c', tends constantly to hold 75 the valve C, to its seat to close the port c, from which the valve C, is raised by an eccentric E, acting against the outer end of the valve stem c', and against the resistance of the spring s.

The eccentric E, is mounted adjustably upon the counter shaft a, so that its thrust may be varied to prescribe the extent to which the port c, is to be opened at each reciprocation of the valve C, and its stem c'. Any well known means may be resorted to in thus providing for the adjustment of the reciprocatory stroke of the valve C, as related to its seat c. In the drawings the eccentric is shown as formed with a central 85 radial slot e, straddling the countershaft a, which is screw-threaded for engagement with the clamping nuts a', a', by which the eccentric E, may be rigidly secured to the said shaft a, in any prescribed position 90 within the limit of the slot. But I do not limit myself to this construction and arrangement of parts for actuating the controlling valve C, which may obviously be manipulated and adjusted by various well 95 100

known mechanical expedients without departing from the spirit and intent of my invention in this respect. In like manner mechanical expedients for varying and prescribing the speed of reciprocation of the controlling valve C, other than herein shown may be resorted to with like effect in so far as this feature of my invention is concerned, the driving cone D, herein represented being chosen as a simple expedient for the purpose, and by way of illustrating the principle involved. Thus the conical driving member D, is shown as rigidly attached to a power shaft P, mounted on a frame Q, which is longitudinally adjustable, and said cone D, contacts peripherally with the tread pulley a^2 , on the countershaft a, which carries the eccentric E, which actuates the valve stem c' , and valve C, as hereinbefore stated. To effect this longitudinal adjustment of the driving cone D, and power shaft P, the frame Q, is mounted between parallel guide ways q , q' , and adjusting screws q , q' , are provided at each end of the frame Q, as shown in Fig 2, whereby the frame Q, may be locked in a prescribed position. The power shaft P, is driven by means of a pulley p' , or any other power transmitting device.

30 It will be noted that the longitudinal axes of the power shaft P, and counter shaft a, are inclined with relation to each other in such manner that the tread pulley is positioned at right angles, or perpendicular, to the side of the driving cone D, with which it contacts. In other words, the upper side of the driving cone D, is parallel to the longitudinal axis of the counter shaft a, so that the longitudinal adjustment of the driving cone D, and the power shaft P, does not affect the contact engagement between the driving cone D, and driven or tread pulley a^2 . But obviously such longitudinal adjustment of the driving cone D, upon the power shaft P, will increase or diminish the speed of rotation of the countershaft a, according to direction of adjustment, and hence the speed of reciprocation of the valve rod c' , and valve C.

50 It will thus be seen that I have disclosed herein practical means not only for varying and prescribing the effective stroke of the valve C, so that it may be made to open the port c, more or less at each reciprocation, but also practical means for varying and prescribing the speed of reciprocation of said controlling valve. Hence I am enabled to regulate the action of the controlling valve C, with accuracy in accordance with the conditions and requirements of use, or in other words, according to the initial pressure of the steam on one side and the operative pressure required in the heating system to be supplied with steam, on the other side

of the port c, it being understood that the expansive properties of the steam passing through the port c, are utilized to the fullest extent in adapting the steam supply to the size and capacity of the heating system in such manner that there will be no excess or surplus to result in waste.

In order to render the supply of steam to the heating system uniform in pressure and flow, and to counteract the fluctuating tendency of the intermittent action of the controlling valve C, I prefer to interpose an equalizing chamber I, between the heating system and the controlling valve C, as shown symbolically in Fig. 1. I thus attain a steady, uniform flow of steam under appropriate pressure to the heating system, much better adapted to the requirements thereof, and much more susceptible of regulation and control, than a rush of steam through the heating system at initial pressure, as in the old method of supply, which it is the object of my invention to supersede, involving as the latter does a large percentage of waste by direct loss of pressure and heat, besides being otherwise unsatisfactory and unscientific.

By my method I hold back the initial volume and pressure of steam in the boiler or other source of supply, drawing upon it only as needed for use, and accurately controlling the amount of steam released or drawn off in accordance with the actual capacity and requirements of the heating system to be supplied. In this connection, of course, the means for regulating the thrust of the valve, or conversely speaking, the available area of the port c, when open, as well as for regulating the speed of operation of the valve, are important factors in attaining the desired result. Thus there can be no waste from the blowing or forcing of an unnecessary amount of steam through the heating system where such excess is not amenable to control, but is, on the contrary, apt to be a source of trouble and annoyance, as well as of waste.

What I claim as my invention and desire to secure by Letters Patent is,—

1. Apparatus for supplying steam to a heating system comprising an equalizing chamber connected therewith, a valve interposed in the steam conduit between said equalizing chamber and a source of steam at initial pressure, means for continuously operating said valve intermittently, and means for regulating the extent of opening of said valve, whereby the expansive properties of the steam are utilized and the pressure adapted to the operative requirements of the system.

2. Apparatus for supplying steam to a heating system comprising an equalizing chamber connected therewith, a valve interposed

in the steam conduit between said equalizing chamber and a source of steam at initial pressure, means for continuously operating said valve intermittently, means for regulating the extent of opening of said valve, and means for varying and regulating the speed of operation of said valve, whereby the ex-

pansive properties of the steam are utilized and the pressure adapted to the operative requirements of the system.

HARRY J. MARKS.
